MAGAZINE OR BOOK STAND

Joseph Paulus, Union, N. J.

Application June 28, 1932. Serial No. 619,639

7 Claims. (Cl. 45—64)

This invention relates, generally, to supports for magazines and books; and the invention has reference, more particularly, to a novel improved magazine or book stand.

5 The principal object of the present invention lies in the provision of a novel magazine or book stand having a central panel and side panels or wings which latter panels may be adjusted angularly to thereby vary the capacity of the stand 10 and at the same time facilitate easy access thereto as for the purpose of inserting magazines or books into or removing them from the stand or for inspecting the contents of the stand.

Another object of the present invention is to 15 provide a novel magazine or book stand having simply designed positive means for holding the said side panels or wings in desired angular positions, the said panels being readily movable from one position to another when desired, the range 20 of adjustment of said panels being from a substantially vertical position to a horizontal position.

Still another object of the present invention lies in the provision of a novel magazine or book 25 stand which is of compact and attractive appearance, the size of the same being variable in accordance with the number of magazines or books held thereby, the said stand serving to retain magazines in smooth and unwrinkled condition.

30 Other objects of this invention, not at this time more particularly enumerated, will be clearly understood from the following detailed description of the same.

The invention is clearly illustrated in the accompanying drawings, in which:

Fig. 1 is a view in side elevation of the novel magazine or book stand of this invention showing the side panels in their raised positions.

Fig. 2 is a plan view of the structure shown in Fig. 1.

Fig. 3 is a view in end elevation of the structure shown in Fig. 1, there being illustrated in dotted lines in this figure, the positions assumed by the side panels while inserting magazines or books into or removing them from the said stand.

Fig. 4 is a view similar to Fig. 3 but shows the side panels inclined or turned down somewhat with respect to their positions shown in Fig. 3.

50 Fig. 5 is a plan view of the stand showing the side panels or wings in horizontal position; and

Fig. 6 is an enlarged fragmentary view showing the manner of operating the side panels or wings.

55 Similar characters of reference are employed

in all of the hereinabove described views to indicate corresponding parts.

Referring now to said drawings, the reference numeral 1 designates the novel magazine or book stand of the present invention as a whole. This stand comprises vertical end legs 2 and 3 which are joined near their bottoms by a fixed book shelf or trough 4. The trough 4 not only serves to hold books or other articles, but also serves to brace the legs 2 and 3.

A horizontally extending panel or platform 5 has its end portions fixedly supported upon the tops of the legs 2 and 3, the said platform forming, with the legs 2 and 3 and the trough 4, a rigid supporting structure. A drawer 14 underlies the platform 5 and is provided with a lateral extension 15 through which a vertical supporting screw 16 passes. The screw 16 is threaded into the platform 5 and serves as a pivotal support for the drawer 14, thereby enabling this drawer to be turned outwardly of the platform 5, as illustrated in Fig. 5. Thus, by turning this drawer outwardly, ready access is had thereto as for inserting articles into the same or for removing articles therefrom.

Centrally of the platform 5 is positioned an upwardly extending stationary panel 6. The panel 6 preferably comprises a rectangular frame, the end members 7 of which have lower projecting portions that extend downwardly at the sides of the legs 2 and 3 and are secured to these legs as by screws 8. The upper and lower members of the frame 6 are illustrated as interconnected by spaced slats 9 (see Fig. 5). A handle 10 is secured to the upper horizontal member of the frame of panel 6 and serves as a convenient means for carrying the stand around, when desired.

The end members 7 of the frame are illustrated as having annular ash receptacle supports 11 hingedly connected thereto at 17. The supports 11 are adapted to carry ash receptacles 12 and these supports may be turned from their upwardly and out-of-the-way positions, shown in full in the drawings, to the horizontal dotted line useful positions also shown in the drawings. Snap catches contained within lugs 13 mounted on the end members 7 are adapted to retain receptacle supports 11 in their up-turned positions, when desired.

Similar angularly adjustable side panels or wings 19 and 19' are located on opposite sides of the central panel 6. As these side panels 19 and 19' are similar in construction and similarly mounted upon the platform 5, only one of these

panels, namely, the panel 19, will be described in detail.

As shown in the drawings, panel 19 consists of a substantially rectangular frame having upper and lower horizontal members 20 and 21 and similar end members 22. A plurality of spaced slats 23 serve to interconnect the upper and lower members 20 and 21. The end members have lower projecting portions 26 extending beyond the lower horizontal member 21, which projecting portions are provided with longitudinally extending slots 24. Pivotal supporting screws 25 extend through the slots 24 and are threaded into the platform 5 adjacent the side edge of this plat-

15 form. The side panel 19 is adapted to be turned upon the pivotal screws 25 so that the angular position of this panel may be selectively varied from that shown in Fig. 3 to the horizontal position shown in Fig. 5.

20 The projecting end portions 26 of the panel 19 are adapted to cooperate with spaced pins 27 and 28 which are provided at each end of the stand. The pins 27 at the respective ends of the stand are in axial alignment and are secured in the 25 legs 2 and 3, the said pins projecting from these legs for engaging the end portions 26. Pins 28 at the respective ends of the stand are also in axial alignment and are secured in the legs 2 and 3, the said pins projecting from these legs for engaging the end portions 26. The projecting end portions 26 have bevels 29 at their outer sides for facilitating the movement of these end portions over the pins 27 and 28 when the panel 19 is turned upwardly in use.

25 Pins 27 are so positioned with respect to the pivotal screws 25 that when the straight sides of the projecting end portions 26 engage these pins as illustrated in dotted lines in Fig. 3, the panel 19 is inclined slightly from the vertical and toward 30 the central panel 6 so that the said panel 19 will inherently move under the action of gravity toward and engage the central panel 6 as shown in full lines in Fig. 3. In other words, the slight inclination of the panel 19 toward the central panel 6, when its projecting end portions 26 engage pins 27, causes this panel to fall toward the central panel 6, so as to engage this panel in the event that no magazines or books occupy the space between these two panels. In the event 35 that a magazine, for example, is positioned in the receiving space between stationary panel 6 and movable side panel 19, the said side panel, by pressing the magazine against the central panel 6, serves to support the magazine and prevents the normal sagging of the same which would otherwise occur due to its weight.

If it is desired to insert only a few magazines or books into the receiving space extending between panel 19 and panel 6 of the stand, the panel 19 may be left in its positions shown in Figs. 1 to 3, and while inserting the magazines or books into or removing them from such receiving space, it is merely necessary to move the panel 19 momentarily outwardly somewhat into the dotted line position shown in Fig. 3, whereupon such insertion or removal of books may be accomplished, the pins 27 serving to limit the outward movement of the panel to the dotted line position.

70 When it is desired to insert a greater number of magazines or books into the variable receiving space of the stand, the panel 19 may be raised or moved rectilinearly somewhat momentarily so that the lower portions of projections 26 clear the pins 27, whereupon the panel may be turned downwardly, thereby bringing projections 26

against pins 28. The slots 24 provided in the projections 26 permit such raising of the panel 19 with respect to the pivotal screws 25 while at the same time these slots, by limiting the movement of the projections 26 with respect to the pivotal screws, also serve to prevent the accidental complete removal of the panel 19 from the screws 25. The lower end portions of projections 26 now abut pins or stop members 28, as shown in Fig. 4. The panel 19 is now outwardly inclined with respect to central panel 6, thereby enabling a greater number of magazines or books to be inserted into the receiving space between panel 19 and central panel 6.

90 In the event that it is desired to insert still more magazines or books into the receiving space between panel 19 and central panel 6, the panel 19 may again be momentarily raised somewhat so that its end projections 26 clear pins 28, thereby permitting the panel 19 to be turned downwardly and into the horizontal position shown in dotted lines in Fig. 4 and in full lines in Fig. 5. When in such horizontal position, the straight side of each of the projecting portions 26 engages a stop lug 30 provided on the side of an end member 7 100 of the central panel 6. (see especially Figs. 4 and 6).

With the side panel 19 in its horizontal position, the same serves, in effect, as a table, thereby providing an enormous capacity for the stand. 105 The same is true of panel 19', the parts of which are numbered similarly to those of panel 19. With both panels 19 and 19' in their horizontal positions, as shown in Fig. 5, the stand is open to its maximum capacity and may be used not only for supporting books or magazines, but may be used as a table, if desired. With these panels in their horizontal positions, should it be desired to again raise the same, to their vertical positions shown in Fig. 3, it is merely necessary to turn these panels upwardly and toward the central panel 6, during which movement the bevels 29 of the projecting end portions of these panels cause these projecting end portions to ride readily over the pins 27 and 28.

110 It will thus be noted that the novel magazine or book stand of the present invention is readily adjustable from a minimum capacity shown by the positions of the side panels in Fig. 3 to a maximum capacity shown in Fig. 5, the said adjustment being made with a minimum of effort. The stop pins 27 and 28 and the stop lugs 30 serve to positively hold the side panels in their selected adjusted positions. It will be apparent that a greater number of the pins 27 and 28 may be used, if desired, thereby providing for a greater number of angular adjustments of the side panels. It will be noted that the space occupied by the stand will vary in accordance with the number of magazines and books held thereby, so that the same may be caused to occupy a minimum of space at all times.

115 As many changes could be made in the above construction and many apparently widely different embodiments of this invention could be made without departing from the scope thereof, as defined by the following claims, it is intended that all matter contained in the above description or shown in the accompanying drawings shall be interpreted as illustrative and not in a limiting sense.

120 What is claimed is:

1. In a magazine or book stand, a support, a panel pivotally connected to said support, a plurality of consecutively disposed stop members

- 5 carried by said support for engaging said panel to hold the same in any one of a plurality of selected angular positions about said support, said panel being arranged for rectilinear movement with respect to its pivotal connection on said support, whereby said panel may be caused to pass over one stop member during its movement to engage another stop member.

10 2. In a magazine or book stand, a support, a panel pivotally connected to said support, a plurality of consecutively disposed stop members carried by said support for engaging said panel to hold the same in any one of a plurality of selected angular positions about said support, said panel being arranged for rectilinear movement with respect to its pivotal connection on said support, whereby said panel may be caused to pass over one stop member during its movement to engage another stop member, and means provided on said panel for limiting the rectilinear movement thereof with respect to its pivotal connection, thereby preventing the accidental removal of said panel.

15 3. In a magazine or book stand, a support, a fixed panel extending upwardly from said support, a second panel pivotally connected to said support, stop members carried by said support for engaging said second panel to hold the same in selected angular positions with respect to said fixed panel, said second panel being arranged for rectilinear movement with respect to its pivotal connection on said support, whereby said second panel may be caused to pass over one stop member during its movement to engage a selected stop member, a certain one of said stop members being positioned so that when the second panel is moved into engagement with the same, the said second panel will turn under the influence of gravity and into engagement with the fixed panel.

20 4. In a magazine or book stand, a support, a fixed panel extending upwardly from said support, a second panel pivotally connected to said support, at points spaced from said fixed panel, said second panel being angularly adjustable in steps with respect to said fixed panel, stop members carried by said support, said second panel having slots therein at its pivotal connections with said support, said slots providing for rectilinear movement of said second panel with respect to its pivotal connections on said support, whereby said panel may be shifted to pass the same over

25 some stop members during its movement to engage selected stop members.

5. In a magazine or book stand, a platform, legs supporting said platform, a panel fixed to said platform and extending upwardly therefrom, a second panel pivotally mounted on said platform in spaced relation to said fixed panel, thereby providing a magazine or book receiving space between said panels, stop members carried by said legs for engaging said panel to hold the same in selected angular positions about said platform, the pivotal connection of said second named panel providing for rectilinear movement of the panel, whereby the same may be caused to pass over some of said stop members in its movement to engage others of said stop members.

30 6. In a magazine or book stand, a platform, legs supporting said platform, a panel fixed to said platform and extending upwardly therefrom, a second panel positioned adjacent said fixed panel, said second panel having slots therein, pivotal screws carried by said platform and extending through said slots for pivotally connecting said second panel to said platform, a plurality of stop members carried by said legs and disposed for engaging said second panel to hold the same in selected angular positions with respect to said fixed panel, said slots enabling said second panel to be moved rectilinearly so as to clear stop members when angularly adjusting the same, said slots also serving to prevent total removal of said second panel.

35 7. In a magazine or book stand, a platform, legs supporting said platform, a panel fixed to said platform and extending upwardly from the center thereof, a pair of side panels positioned at the sides of said fixed panel, said side panels having slots therein, pivotal screws carried by said platform and extending through said slots for pivotally connecting said side panels to said platform, a plurality of stop members carried by said legs and said fixed panel, said stop members being disposed for engaging said side panels to hold the same in selected angular positions with respect to said fixed panel, said slots enabling said side panels to be moved rectilinearly so as to clear stop members when angularly adjusting the same, said slots also serving to prevent total removal of said side panels.
